COMBINED STORAGE CONTAINER AND TABLE

James F. Stewart, 10320 Claudia,
Boise, Idaho 83702

Filed Feb. 9, 1973, Ser. No. 331,162

Term of patent 14 years

Int. Cl. D6—04

U.S. Cl. D6—170

FIG. 1

FIG. 2

FIG. 3

FIG. 1 is a left front perspective view of a combined storage container and table showing my new design on an enlarged scale;

FIG. 2 is a perspective view in the opposite direction;

FIG. 3 is a perspective view in partially open position; and

FIG. 4 is a perspective view in open position with table extended.

I claim:

The ornamental design for a combined storage container and table, substantially as shown and described.
